UNITED STATES PATENT OFFICE.

EDWARD FULDA, OF NEW YORK, N. Y., ASSIGNOR TO CHARLES F. TISCHNER, JR., OF NEW YORK, N. Y.

METALLIC WHEEL.

1,177,179.

Specification of Letters Patent. Patented Mar. 28, 1916.

Application filed February 8, 1916. Serial No. 76,893.

To all whom it may concern:

Be it known that I, EDWARD FULDA, a citizen of the United States, and a resident of New York, in the county of New York and State of New York, have invented certain new and useful Improvements in Metallic Wheels, of which the following is a specification.

My invention relates to the construction of wheels made of metal or similar material and its object is to provide a wheel having tubular spokes and preferably also tubular rim or felly and of such construction that it shall be light, strong, cheap and durable and shall at the same time have, if desired, the appearance of an ordinary wooden wheel provided with spokes as in the wellknown artillery type of wheel employed for automobiles or other uses.

To these ends my invention consists in the construction of wheel hereinafter described and more particularly specified in the claims at the end of this specification.

In the drawings, Figure 1 is a side elevation of a wheel embodying my invention. Fig. 2 is a vertical cross-section on the line 2—2 of Fig. 1. Fig. 3 is a side elevation of one of the spacing plates employed to connect the two side plates and itself constituting a portion of the wall of the tubular spokes and rim. Fig. 4 is an enlarged cross-section through said spacing plate taken on the line 4—4, Fig. 3. Fig. 5 shows in side elevation one of the side plates or stampings, two of which are used in conjunction with the interposed spacing plates to produce a wheel having tubular spokes and preferably also a tubular rim. Fig. 6 is a cross-section through one of the side plates taken on the line 6—6, Fig. 5. Fig. 7 is an enlarged cross-section through the tubular spoke of the completed wheel, and taken on the line 7—7, Fig. 1.

1, 1' indicates the side plates stamped or cut out from a sheet of metal or other suitable material to form the sides of the spokes and the sides of the rim or felly. When said rim is constructed as a tubular rim or felly the circumference of said side plates or stampings is suitably extended as shown to form the side wall of said tubular rim. Each said plate or stamping is made of a single piece of metal and is continuous. They are spaced apart and held together by interposed metal plates 3 located at the edges of

the sector-shaped openings formed in the plates 1, 1' and suitably interlocked with the plates 1, 1' by the turned-over edges 5 of the plates 3. Said spacing members or plates 3 may be formed from a rolled plate of metal 60 of the form in cross-section shown in Fig. 4, said plate being bent up to the sector-shape shown in Fig. 3 adapting it to fill the edges of the sector-shaped opening in the plates 1, 1'. The spacing member or plate 3 completes one side of each of two adjoining tubular spokes and constitutes in effect the edge wall of said tubular spoke as clearly shown in the cross-section Fig. 7 taken transversely through the spoke of the completed 70 wheel.

When the wheel is constructed with a tubular rim said plate, as shown in the section Fig. 2, constitutes likewise a portion of the wall of said tubular rim at the inner edge 75 thereof. It will also, in the particular construction of wheel shown, constitute an outside wall of the hub portion of the wheel when the side plates extend inwardly toward the center of the wheel for attachment 80 of the usual hub bearings, the hub portion of the plates being, in such case, preferably strengthened by the annular strengthening rings 8, 9 inserted between them, as shown in the section Fig. 2.

To complete the structure of the tubular rim the continuous circumferential spacing plate 6 is interposed between the edges of the side plates at their outer periphery and is interlocked therewith by turned-over edges 90 7 of said plate 6. Said plate 6, like the plate 3, is preferably provided with spacing ribs or projections 4 preferably formed integral therewith and extending over the whole length of the plate, said projections or ribs 95 serving to locate and hold the side plates 1, 2 spaced apart in obvious manner.

Obviously, it is not necessary to my invention that said spacing projections or ribs should be integral with the plate 3 since 100 they might be formed of a separate plate or body secured to plate 3 in any desired way.

In the work of constructing the wheel the side plates are seated against the flanges or projections 4 of the spacing plates 3 and 6 105 and the edges 5 and 7 of said plates are turned over in a press thus interlocking the side plates and spacing plates. As shown, the side plate 1, 1', are made perfectly flat in construction in their spoke and rim por- 110

tions but obviously said portions might be slightly rounded to give a rounded effect when the wheel is seen in side view. Also, as will be obvious, by varying the width of 5 the spacing plates it is easy to make a wheel of any width and by using the same dimensions of side plate. By this construction it is obvious that any taper desired may be readily given to the spokes.

10 If desired the joints between the side plates and the spacing members may be brazed or the whole wheel may be dipped in brazing material whereby any rubbing of the parts is prevented and all spaces 15 closed against rust, dirt and other matter.

What I claim as my invention is:—

1. A metal wheel having tubular spokes and comprising two members consisting of complementary metal plates each having a 20 spoke and felly portion and a third member consisting of a plurality of continuous sector-shaped pieces of metal inserted between said plates to complete the walls of the tubular spokes and locked thereto by folded 25 or turned-over metal forming an edge of the sector-shaped pieces.

2. A metal wheel having tubular spokes and rim and comprising two complementary metal plates each forming a side of the 30 spokes and rim, combined with spacing members consisting of plates interposed between them and forming edge walls of the spokes and of the inside of the tubular rim and secured to said complementary members by the turned-over edge of said spacing 35 members.

3. A wheel having tubular spokes and tubular rim and comprising essentially two side plates each consisting of a single piece 40 of metal and each forming one side of the spokes and rim, combined with spacing members inserted in the segmental spaces between spokes and spacing the two complementary members apart while at the 45 same time forming the edge walls of the spokes and the wall for the inner edge of the tubular rim, said spacing members having an overturned edge locking them and the side plates together, and a peripheral continuous plate filling the space between the 50 peripheral edges of the said side plates and interlocked therewith by a turned-over edge thereof to complete the tubular rim.

4. In a wheel having tubular spokes, the 55 combination of two complementary metal stampings each forming one side of the spokes and interposed metal spacing members interposed between said complementary members to form the edge walls of the 60 spokes and locked thereto by the bent-over metal of said spacing members.

5. In a metal wheel having tubular spokes, the combination of two side plates each forming a side wall of the spokes and also 65 a side of the rim combined with spacing

plates provided with spacing projections upon which the side plates seat, said spacing plates forming edge walls of the tubular spokes and being interlocked with the portion of the side plates forming the side walls 70 of said spokes by the bent-over edge of the spacing plates.

6. In a metal wheel having tubular spokes, the combination with two complementary metal stampings forming the side walls of 75 the tubular spokes and spacing sector-shaped plates interposed between the same to form the walls for the edges of the spokes, said spacing plates each consisting of a rolled metal plate having spacing projections near 80 their edges, said edges being turned over to lock said metal stampings and spacing plates together.

7. A metal wheel having tubular spokes and rim and composed essentially of two 85 complementary metal stampings each forming a side wall of the tubular spokes and a side wall of the rim, combined with spacing plates consisting of rolled metal having spacing ribs near their edges and interposed between said stampings to form the edge walls of the spokes and the wall at the inside of the tubular rim, and a continuous spacing circumferential plate interposed between said stampings at their periphery and 90 locked thereto by bent-over metal and adapted to form the wall at the outside of the tubular rim.

8. In a tubular metal wheel, the combination of two members consisting of plates 100 forming each a side wall of the tubular spokes and rim and continuous metal plates bent to sector shape and interposed between and interlocked with said members to form a part of the wall of two adjoining hollow 105 spokes and a portion of the wall of the tubular rim at the inside edge thereof.

9. In a metal wheel having tubular spokes and tubular rim, the combination of two complementary metal stampings each forming a side wall of the spokes and also a side wall of the rim combined with spacing plates provided with spacing projections upon which the metal stampings seat, said spacing plates forming edge walls of the 115 tubular spokes and locked to the portion of the metal stampings forming the side walls of said spokes by the bent over edges of the spacing plates and a continuous band joining the outer edges of the stampings and 120 forming the outer periphery of the tubular rim.

10. In a metal wheel having tubular spokes and rim, the combination of two complementary metal stampings each forming a side wall of the hollow spokes, rim and hub, continuous sector-shaped metal plates spacing said complementary members apart and locked thereto by bent over edges of the spacing plates, said spacing plates 125 130

being continuous pieces of metal each forming a wall of two adjoining hollow spokes, an outside wall of the hub and an inside wall of the tubular rim in the space between 5 adjoining spokes and annular strengthening rings in the hub portion between the complementary metal stampings.

Signed at New York, in the county of New York and State of New York, this 7th day of February, A. D. 1916.

EDWARD FULDA.
